Primary Examiner — Cynthia R Underwood*(74) Attorney, Agent, or Firm* — Kelly & Kelley, LLP(57) **CLAIM**

The ornamental design for a hinge, as shown and described.

DESCRIPTION

FIG. 1 is a perspective view of a first embodiment of a hinge embodying my new design;

FIG. 2 is an opposite perspective view of the hinge of FIG. 1;

FIG. 3 is a front view of the hinge of FIG. 1;

FIG. 4 is a side view of the hinge of FIG. 1;

FIG. 5 is an opposite side view of the hinge of FIG. 1;

FIG. 6 is a plan view of the hinge of FIG. 1;

FIG. 7 is a bottom view of the hinge of FIG. 1;

FIG. 8 is a perspective view of a second embodiment of a hinge;

FIG. 9 is an opposite perspective view of the hinge of FIG. 8;

FIG. 10 is a front view of the hinge of FIG. 8;

FIG. 11 is a side view of the hinge of FIG. 8;

FIG. 12 is an opposite side view of the hinge of FIG. 8;

FIG. 13 is a plan view of the hinge of FIG. 8; and,

FIG. 14 is a bottom view of the hinge of FIG. 8.

The broken lines represent portions of the structure or environment that form no part of the claim.
